US0D1076846S

(12) **United States Design Patent** (10) **Patent No.:** **US D1,076,846 S**
(45) **Date of Patent:** **** May 27, 2025**

(54) **ELECTRONIC DISPLAY ASSEMBLY**

(71) Applicant: **Manufacturing Resources International, Inc.**, Alpharetta, GA (US)

(72) Inventors: **William Dunn**, Alpharetta, GA (US); **Mike Brown**, Cumming, GA (US)

(73) Assignee: **Manufacturing Resources International, Inc.**, Alpharetta, GA (US)

(**) Term: **15 Years**

(21) Appl. No.: **29/962,649**

(22) Filed: **Sep. 12, 2024**

(51) LOC (15) Cl. **14-03**

(52) U.S. Cl.

USPC **D14/129**

(58) **Field of Classification Search**

USPC D14/129, 302–307, 900–902; D13/163; D20/10; D21/332, 325, 369, 370

CPC G06Q 30/02; G06Q 30/06; A47F 9/047

See application file for complete search history.

CLAIM

The ornamental design for an electronic display assembly, as shown and described.

DESCRIPTION

FIG. 1 is a front perspective view of the electronic display assembly;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

The broken lines illustrate environmental features and unclaimed portions of the electronic display assembly.

1 Claim, 6 Drawing Sheets
